UNITED STATES PATENT OFFICE.

EVERETT LLOYD, OF SAN ANTONIO, TEXAS.

DESIGN FOR A PORTABLE ADVERTISING BOARD.

Application filed May 14, 1926. Serial No. 17,723. Term of patent 7 years.

To all whom it may concern:

Be it known that I, EVERETT LLOYD, a citizen of the United States, residing at San Antonio, in the county of Bexar and State of Texas, have invented a new, original, and ornamental Design for Portable Advertising Boards, of which the following is a specification, reference being had to the accompanying drawing, forming part hereof.

The figure is a front elevational view of a portable advertising board, showing my new design.

I claim:

The ornamental design for a portable advertising board, as shown.

EVERETT LLOYD.
